CURTAIN FIXTURE

William S. Hamm, Elkhart, Ind., assignor to The Adlake Company, Chicago, Ill., a corporation of Illinois

Application November 16, 1935, Serial No. 50,067

4 Claims. (Cl. 156—26)

The purpose of this invention is to provide a curtain fixture of improved construction which is operated by rotating a centrally located knob a part of a turn in either direction. The improved fixture is of pleasing appearance, can be manufactured inexpensively, is absolutely noiseless and will hold a curtain firmly in any position in which placed.

Other more specific objects and advantages of the invention will be apparent to those skilled in the art upon a full understanding of the construction, arrangement and operation of the parts entering into the complete organization.

A preferred embodiment of the invention is presented herein, but it will of course be appreciated that such embodiment is intended primarily for the purpose of exemplification and that the invention is susceptible of being embodied in other structurally modified forms coming equally within the scope of the appended claims.

In the accompanying drawing:

Fig. 1 is an inside front view of a window curtain assembly equipped with the new fixture;

Fig. 2 is a vertical transverse section through the fixture, taken on the line 2—2 of Fig. 1;

Fig. 3 is a similar section, taken on the line 3—3 of Fig. 1;

Fig. 4 is a vertical longitudinal section through one end of the fixture;

Fig. 5 is a horizontal section, taken on the line 5—5 of Fig. 4;

Fig. 6 is a horizontal section through the center of the fixture, taken on the line 6—6 of Fig. 1; and

Fig. 7 is a vertical longitudinal section, taken on the line 7—7 of Fig. 6.

As will be observed in the drawing, the fixture includes a tube 10, an operating knob 11 midway between the ends of the tube, and heads 12 beyond the ends of the tube. The tube 10, which is preferably made of either sheet or extruded metal, is vertically elongated in cross section, with narrow upper and lower sections and a relatively wide rectangular intermediate section 13, and is provided along its upper edge with a partially closed groove 14 in which the lower edge of the curtain 15 is securely held by a small filler rod 16 inserted from one end of the tube.

The heads 12 are preferably equipped with rubber blocks 17, but they may be furnished with any other suitable device for frictionally engaging with the vertical guides 18 at the sides of the window opening. As both of the heads 12 and their associated control members are the same, only one of the heads and its control mem-

bers will be described in detail. As shown in Fig. 4, the left-hand head 12 is provided with a stem 19 which extends into the end of the tube 10 through a hole in a wood block 20 which is fixedly positioned in the wide intermediate section 13 of the tube. The hole in the block 20 forms a guideway for the stem of the head to slide back and forth in, and the outer part of the hole is enlarged to provide a pocket for a spring 21 which is coiled about a reduced portion of the stem between a shoulder 22 on the block and a shoulder 23 on the stem. The spring 21 tends at all times to project the head 12 outwardly into firmly holding frictional engagement with the guide 18.

The inner end of the stem 19 is threaded into a small sleeve 24 which is slidably mounted in an enlargement at the inner end of the hole in the block 20, and the sleeve 24 is in turn pivotally attached to one end of a long rod 25. The end of the sleeve 24 which is connected with the rod 25 is bifurcated, as best shown in Fig. 5, and the adjacent end of the rod 25 is flattened to fit within the bifurcation. A pivot pin 26 is mounted in the bifurcated end and passes through an aperture in the flattened portion of the rod, which aperture is elongated axially of the rod to permit of a certain amount of endwise movement of the rod relative to the sleeve and its associated stem and head. This endwise movement is normally prevented by the resistance of a spring 27 which is mounted on the rod 25 near the pivotal connection and is compressed between a washer 28 secured to the rod and another washer 29 abutting against the end of the sleeve. The far end of the rod 25 terminates adjacent the location of the knob 11 in two oppositely spring-pressed strips 30 which are riveted to the rod and are provided at their free ends with laterally projecting studs 31.

The rods 25 leading to both heads are connected to a rotatable hub 32 which is located in the tube 10 behind the knob 11. The knob has a reduced neck portion 33 which is journaled in a circular aperture cut in the front face of the tube, and the hub 32 is clamped to the inside face of the knob by a screw 34 which passes through the center of the knob and is threaded into a recess in the center of the hub. The end of the hub which is clamped to the knob is larger than the neck portion and accordingly locks the knob against outward movement. The hub is centered on the knob by means of the screw 34 and is caused to turn positively with the knob by means of a rib 35 on the inside face of the knob which fits into a complementary groove 36 on the ad-

jacent end of the hub. The hub 32 is of generally cylindrical shape, with segments cut out of opposite sides between the ends, which segments leave two pairs of spaced ears 37. The strips 5 30 on the inner ends of the rods 25 are sprung together to fit between the ears 37, and when so fitted the studs 31 on the ends of the strips snap into recesses in the ears and establish pivotal connections between the ends of the rods and the hub eccentrically of the axis of the latter. The strips 30 are preferably provided, in the spaces between the same, with yieldable pads 38 of felt or other suitable cushioning and sound-deadening material.

15 Near the hub 32 the rods 25 are provided with springs 39 which project upwardly and downwardly at an angle from the rods and are provided with bent foot portions 40 which abut with the inside walls of the tube 10 in the enlarged 20 intermediate section 13 thereof. These springs, in addition to supplementing the action of the springs 21 in tending to force the heads into engagement with the guides, tend to keep the rods 25 centered in the tube and free from all up-and-25 down as well as sidewise play.

When the fixture is first installed, the heads 12 are screwed either in or out in the sleeves 24 in order to cause the heads to engage with the guides 18 just before the pivotal connections between the hub 32 and the rods 25 reach their 30 dead center positions.

To retract the heads from the guides in raising or lowering the curtain, it is merely necessary to rotate the knob 11 a part of a turn in either 35 direction. It doesn't make any difference in what direction the knob is turned because if it is started in a direction which would project the heads instead of retract them the rods 25 will pass through their dead center positions without 40 any difficulty due to the resiliently yieldable couplings in the rods afforded by the springs 27.

In assembling the several parts of the fixture at the time of its manufacture, the rods 25 are hooked up with the hub 32 and all of the inside 45 mechanism is then threaded through the tube 10 at the same time. Then when the hub 32 is brought into register with the aperture at the center of the tube the knob 11 is placed in position in the aperture and the hub 32 is drawn up 50 tightly against it by means of the screw 34.

I claim:

1. In a curtain fixture, an outwardly movable head at one end of the fixture for engagement with a guide at one side of the curtain, a spring for pressing the head outwardly, a rod connected with the head, a rotatable operating member connected at a point eccentrically thereof with the rod, and a resiliently yieldable coupling between said operating member and said rod so constructed and arranged as to permit the operating 10 member to be rotatable in either direction past the dead center position of the rod in retracting the head.

2. In a curtain fixture, an outwardly movable head at one end of the fixture for engagement 15 with a guide at one side of the curtain, a spring for pressing the head outwardly, a sleeve threadingly connected with the head, a rod pivotally connected with the sleeve, and a rotatable operating member connected at a point eccentrically 20 thereof with the rod for retracting the head.

3. In a curtain fixture, an outwardly movable head at one end of the fixture for engagement with a guide at one side of the curtain, a spring for pressing the head outwardly, a sleeve threadingly connected with the head, a rod pivotally connected with the sleeve, a rotatable operating member connected at a point eccentrically 25 thereof with the rod, and a resiliently yieldable coupling at the location of the pivotal connection 30 between the sleeve and the rod so constructed and arranged as to permit the operating member to be rotated in either direction past the dead center position of the rod in retracting the head.

4. In a curtain fixture, a tube adapted to be 35 secured to the lower end of a window curtain, an outwardly movable head at one end of the tube adapted to engage with a guide at one side of the window, a rotatable member mounted in the tube midway between the ends of the latter, 40 a link in the tube pivotally connected at its outer end to the head and at its inner end to the rotatable member at a point eccentrically of the latter, whereby rotation of said member away from a dead center position will retract the head, a spring 45 acting against the head to project the latter, and another spring acting against the link to augment the effect of the first mentioned spring and hold the adjacent end of the link against lateral play.

WILLIAM S. HAMM. 50
